UNITED STATES PATENT OFFICE

EDWARD O. HERMANN, OF MILL VALLEY, CALIFORNIA, ASSIGNOR TO COBB CONNECTOR COMPANY, OF LOS ANGELES, CALIFORNIA, A CORPORATION OF ARIZONA

TRAIN PIPE COUPLER SUPPORT

Application filed September 12, 1928. Serial No. 305,462.

My present invention relates broadly to a support for train pipe couplers and more particularly to a support for train pipe couplers of the type contemplated by my co-pending application for Letters Patent, Serial Number 305,461, filed September 12, 1928.

An object of my invention is to provide a novel form of support for train pipe couplers which will permit a substantially universal movement of the coupler head.

A further object of my invention is to provide in a support of the character contemplated by my invention a centering means which will maintain the supported coupler centrally of the car when disconnected so that when approaching a cooperating coupler head, it will align therewith.

Other objects and advantages of my invention will appear hereinafter as the description, taken in connection with the accompanying drawings, proceeds.

For a better understanding of my invention, reference should be had to the accompanying drawings, in which I have shown a preferred embodiment of my invention and, while I have shown by way of illustration a very specific structure, it is to be understood that, in adapting the same to meet the many conditions that may arise, various changes in the form, design, proportion, and minor details of construction may be resorted to without departing from the spirit and scope of my invention.

In the drawings—

35 Figure 1 is a sectional elevation of my improved coupler support taken along the longitudinal center line thereof.

Figure 2 is a front elevation in section taken along line II—II of Figure 1,

40 Figure 3 is a plan view in section, taken along line III—III of Figure 1,

Figure 4 is a front elevation of the coupler support with the projecting end of the support in section,

45 Figure 5 is a plan view of the coupler support and housing, and

Figure 6 is a front elevation in section taken along the line VI—VI of Figure 1.

50 In the supporting of train pipe coupler heads of the character contemplated by my

invention, because of their great weight, it is essential that a support of corresponding strength be provided. It is also essential, in addition to providing sufficient strength, to provide a support which will permit a movement of the coupler head with respect to the support so that the two cooperating coupler heads will not be subjected to strains due to disalignment which would tend to break their connection with each other.

In order to meet these conditions, I have provided a coupler support of such a construction that it not only possesses the strength required, but in addition will permit of a substantially uniform movement of the coupler head with respect to the support.

In describing my invention in connection with the accompanying drawings wherein I have shown by way of illustration one embodiment of my invention and wherein like parts are designated by like numerals, I shall, in order to simplify an explanation thereof, describe the apparatus in connection with the several figures in the order numbered.

Before going into a detailed description, however, I shall refer briefly to the several outstanding elements of my improved hanger. Essentially, my invention contemplates the provision of a housing member of substantially rectangular shape, in the forward end of which there is mounted a vertically movable cradle 11. This cradle 11 is spring supported and guided by suitable guides, and pivotally mounted upon vertically extending pivots carried by said cradle there is a drawbar supporting member 12 which projects rearwardly into the housing 10 where it engages a second or horizontally movable cradle 13. The drawbar supporting member 12 is provided with a drawbar 14 which is slidably mounted therein with its end projecting outwardly beyond the housing 10 where it is adapted to support the coupler head. By this arrangement I am able to associate the conjoint movements of said vertically moving cradle, said horizontally moving cradle and the slidable mounting of said drawbar so that the coupler head will be capable of a substantially universal movement with respect to said hanger, as will hereinafter appear.

By referring now to Figure 1, it will be seen that the housing member 10 would, but for the openings in the top, sides, and bottom thereof, form what might be termed a box. The front end of the housing member 10 is closed by a removable end piece 15 through which the drawbar 14 is adapted to project. This front end 15 is provided with a flange 16 along its upper edge and suitable bolts are applied to hold it in place upon the housing. By providing the flange 16, a very rigid connection between the housing 10 and plate 15 is obtained, as it places the bolts at this point under a shearing stress. The cradle 11 is shown as mounted upon a pair of springs 17 immediately behind the end piece 15 and between it and a pair of vertically extending spaced guides 18. The guides 18 and the end piece 15 are each provided with suitable raised surfaces 19 and 20, respectively, between which rollers 21 carried by the cradle 11 move. The cradle 11 has a relatively large central opening through which the drawbar supporting member 12 projects and centrally at the top and bottom thereof there is provided a pair of vertically extending aligned pivots or shafts 22 which engage the drawbar support 12 and permit it to pivot freely thereabout. The rear end of the drawbar support 12 projects into the horizontally movable cradle 13 where it engages two oppositely disposed surfaces or cheeks 23 between which it can slide freely up and down. The cradle 13 is guided in its horizontal movement in a substantially arcuate path by means of radius arms 24 and 25 which respectively connect with pivot pins 26 and 27 located in the top and bottom of the housing 10 and in alignment with the pivots 22 carried by the cradle 11. In addition to the radius arms 24 and 25 which guide the cradle 13, it is provided with suitable anti-friction rollers 28 which engage raised arcuate tracks 29 formed upon the inner top and bottom surfaces of the housing 10 and hold it against vertical movement. Interposed between the top of the cradle 13 and the top of the drawbar carrier 12 there is provided a spring 30 which is adapted to resiliently counterbalance the weight of the drawbar and its attached coupler head so that the latter can move freely up and down when in operation with the cradle 11 as the springs 17 are compressed and extended.

The spring 30 is seated upon a recessed box 31 formed in the top of the cradle 13 and is held under initial compression by means of an adjustable bolt 32 which carries a spring engaging head 33. Cooperating with the spring 30 there is also provided concentrically therewith a second spring 34. This spring 34 is somewhat shorter than the spring 30 and, as a result, comes into play only when the spring 30 has been compressed to a predetermined point. The spring engaging head 33 is shown as contacting with the

drawbar support 12 within a recess at the rear end thereof and, as a result of the radius arms 24 and 25 guiding the cradle 13 to an arcuate path substantially about the center line of the pivots 22, it will be seen that there is no danger of the spring 30 becoming displaced from between the cradle 13 and the drawbar support 12. Further reference to this figure of the drawings in connection with a description of the drawbar construction will be made in describing the showing of Figure 3.

By referring to Figure 2 of the drawings, it will be seen that the cheeks 23 between which the rear end of the drawbar support 12 projects are arranged on parallel vertically extending walls which form a rectangular opening in the cradle 13 within which the support 12 is adapted to move vertically. It will also be seen that the anti-friction rollers 28, previously referred to, are mounted upon the four corners of this rectangular frame with their axes located radially with respect to the pivot points 22 so that the cradle 13 will move in an arcuate path, as previously described. On the outer walls of the rectangular frame portion of the cradle 13 opposite the cheeks 23, there are also provided similar raised surfaces 46 and interposed between the walls of the housing 10 and these surfaces 46 there is provided a pair of oppositely disposed compression springs 47 which operate to maintain the cradle 13 centrally of the housing 10 under normal conditions. These springs are mounted upon suitable spring seats 48 formed in the sides of the housing 10 and are maintained under a predetermined initial compression by means of bolts 49 which carry at the ends thereof suitable spring seats 50.

By referring to Figure 3, it will be seen that the spring seats 48 are recessed from the outside of the casing and provide a seat for suitable nuts which are threaded upon the bolts 49. From this figure of the drawings, it will be seen that the cradle 11 projects horizontally completely across the front end of the housing 10 and that the springs 17 are arranged at the extreme ends thereof. At the point where the ends of the cradle 11 engage the side walls of the housing 10, webs 51 are provided which form a partial housing for the upper ends of the springs 17 and form a bearing surface for the cradle 11 against the side walls of the housing 10, and arranged adjacent each of the springs 17 and between the raised surfaces 19 and 20, the rollers 21 are shown as mounted upon suitable horizontally extending shafts 52 so that the cradle 11 can move freely up and down as corresponding forces are exerted on the coupler head.

In connection with this figure of the drawings, reference should be had to Figure 1, where it will be noted that the drawbar 14

is held within the support 12 by means of transversely extending pins 35 and 36 which engage suitable slots 37 in the sides of the support 12. The pins 35 and 36 pass through suitable spacing collars 38 and 39 and cooperating with these collars 38 and 39 there are provided suitable springs 40 and 41 which, in cooperation with the collars 38 and 39, hold the drawbar member 14 within the

support 12 and at the same time permit it to move axially as forces are exerted thereupon in operation. At the outer end of the support 12 there is provided a roller 42 which engages a raised face 43 formed upon the bottom of the drawbar and attached to the rear end of the drawbar there is provided a bearing member 44 which is adapted to slide freely within the support 12. A similar bearing member 45 is attached to the forward end of the housing 12 through which the drawbar is adapted to slide freely.

Continuing now in connection with Figure 3 of the drawing, it will be seen that the slots 37 are oppositely disposed in the walls 25 of the drawbar support 12 and project substantially throughout its operating length. It will be also seen that the pins 35 and 36 are flattened so that they slide freely within these slots. Where the pins 35 and 36 project through the drawbar 14, it will be seen that there are also provided two sets of slots 53 and 54 which cooperate respectively with the pins 35 and 36 so that these two pins in conjunction with the springs 40 and 41 will 30 operate to maintain the drawbar in a predetermined normal position and at the same time permit its displacement axially in either direction from this normal position, as will hereinafter appear in describing the operation of my device.

Referring now to Figure 4, it will be seen that the end plate 15 extends completely across the front of the housing 10 and has stiffening webs 55 immediately behind the 45 raised guide surfaces 20 so that a stiffening thereof results. This figure of the drawings also shows the large central opening in the front cover through which the drawbar 14 extends. It also very clearly shows the manner of mounting the anti-friction roller 42 and the bearing 45 which cooperate with the drawbar to facilitate a free sliding movement thereof within the support 12.

By referring to Figure 5, it will be seen 55 that the housing 10 has a top surface of considerable area through which bolts or other securing means may be passed for the purpose of securing it to the car frame and, since the location and arrangement of such 60 securing holes will be determined by the construction of the particular car to which the housing 10 is secured, I have omitted showing any means of securing the same thereto. This view of my improved support also very 65 clearly illustrates the shape of the radius

arms 24 and 25 which operate to guide the horizontally moving cradle 13. The radius arm 24 visible in this view of the drawing is shown as shaped in the form of a T, so that where it engages the cradle 13, it may be secured thereto by means of two spaced bolts 70 56 which will function to hold the radius arms 24 and 25 at right angles to and centrally of the cradle 13.

In Figure 6 the arrangement and relative 75 positions of the parts cooperating with the vertically movable cradle 11 are more clearly shown than in any other figure of the drawings. From an inspection of this figure of the drawings, it will be seen that the springs 17 are seated in the bottom of the housing 10 upon suitable bosses 57 and held in place by means of bolts 58 which carry a suitable spring seat 59 at their upper ends. These bolts 57 are adapted to 80 slide freely through the bottom of the housing to thus permit compression of the springs 17 and at their outer ends they carry suitable nuts by means of which the springs 17 may be placed under a predetermined initial 85 compression. In this figure of the drawings, the location of the anti-friction wheels 21 is also very clearly shown, they being mounted upon the shafts 52 which extend between suitable webs formed upon the cradle 11. 90 These wheels 21 project outwardly beyond the sides of the cradle 11 and engage, as previously described, the raised surfaces 19 and 20 formed respectively upon the guides 18 and the end plate 15, the guides 18 with their raised surfaces 19 being located behind the rollers or wheels 21. This figure of the drawings also illustrates the fact that the pivots 26 and 27 are located centrally of the housing 10 and directly in alignment with 100 the pivots 22.

The operation of my device is as follows: It will be assumed first that the drawbar 14 is equipped with a coupler head of the type contemplated by my above referred to 110 pending application and that the same is out of engagement with any other or cooperating coupler head. Under these conditions the springs 17 will carry the weight of the drawbar support, the drawbar, and the attached 115 coupler head and hold the various parts substantially in the position shown in Figure 1. The weight of the coupler head at the end of the drawbar 14 will have a tendency to tip the rear end of the drawbar upwardly and the forces so exerted will be transmitted to the drawbar support 12 over the roller 42 and through the bearing 44 and tend to cause it to tip upwardly. This force will then be transmitted to the spring 30 which 120 will operate to counterbalance the weight of the attached coupler head. The initial compression of the springs 17 and 30 under these conditions will be such that they will hold the drawbar support 12 and the draw- 130

bar in the position shown in Figure 1 without any substantial additional compression thereof, and, as a result, the coupler head will be held in its normal position centrally with respect to the car and at a proper height above the rails with the drawbar 14 held outwardly in its normal position by the joint action of the springs 40 and 41 arranged within the drawbar 14 and its support 12.

It will now be assumed that a coupling is about to be made and the two cooperating coupler heads are about to engage. Under these conditions the coupler heads will engage before the car couplers have engaged and, as a result, the springs 40 and 41 will be put under compression and thus force the two coupler heads into engagement where they will be held after the car coupling has been made. If the coupler heads should not be aligned with respect to their height above the rails, the cradle 11 will move up or down, depending upon which of the coupler heads is to be displaced and, should the cooperating coupler heads be out of alignment with respect to the center line of the car, the engaging ends of the coupler heads will be permitted to swing to one side or the other about the pivots 22 and compress one of the centering springs 47, depending upon to which side the coupler head is moved.

When the two coupler heads have become fully engaged and energized, they will be securely locked together and under these conditions the springs 17, 30, 40, and 41 on the cooperating coupler head supports will yield respectively and thus form a support for each of the coupler heads which will yield to a maximum degree and permit either an easy engagement therewith or a successful operation thereof after the two heads are coupled.

Having thus described my invention, what I claim and desire to secure by Letters Patent is—

1. A hanger for train pipe couplers comprising an enclosed housing member adapted to be secured to a car frame, a vertically movable spring supported cradle mounted within said housing member, a horizontally movable spring centered cradle also mounted within said housing, and a drawbar pivotally connected to said vertically movable cradle and projecting into and cooperating with said horizontally movable cradle, whereby substantially universal movement may be imparted to said drawbar with respect to said hanger.

2. A hanger for train pipe couplers comprising an enclosed housing member adapted to be secured to a car frame, vertically extending guides in the forward part of said housing member, a vertically movable spring supported cradle mounted between said guides, horizontally extending trackways in

the rear of said housing member, a horizontally movable spring centered cradle mounted to move upon said trackways, and a drawbar pivotally connected to swing horizontally on said vertically movable cradle and projecting into and cooperating with said horizontally movable cradle, whereby substantially universal movement may be imparted to said drawbar with respect to said hanger.

3. A hanger for train pipe couplers comprising a supporting member adapted to be secured to a car frame, a vertically movable spring supported cradle in the forward part of a housing, a drawbar receptacle secured to said cradle upon vertically extending pivots and projecting rearwardly thereof, a horizontally movable cradle in the rear part of said housing adapted to guide the rearwardly projecting end of said drawbar receptacle, spring means for maintaining said horizontally movable cradle centrally of said housing, a drawbar slidably mounted within said receptacle and adapted to carry a coupler head, and a spring means cooperating with said horizontally movable cradle and engaging the rear end of said rearwardly projecting receptacle adapted to counterbalance the weight of said drawbar and its supported coupler head, whereby the latter may move freely with respect to said hanger to all normal operating positions.

4. In a hanger for train pipe couplers, the combination of a support adapted to be secured to the car frame, a vertically movable cradle mounted upon one end of said support and adapted to carry a drawbar, a pair of parallel vertically extending guides between which said cradle moves, and a roller upon each side of said cradle operating between said guides to prevent longitudinal displacement of said cradle.

5. In a hanger for train pipe couplers, the combination of an enclosed housing, a vertically movable cradle mounted in one end of said housing, a second cradle adapted to move horizontally within the other end of said housing, anti-friction means cooperating with said second cradle and housing to permit a free movement therebetween, and a radius arm having one end pivotally connected to said housing and in line with the central point of said vertically movable cradle and its other end in fixed relation with said cradle, whereby said horizontally movable cradle will move in an arc with respect to said vertically movable cradle.

6. In a hanger for train pipe couplers, the combination of a support, a vertically movable cradle mounted in one end of said support, a second cradle adapted to move horizontally within the other end of said support, anti-friction means cooperating with said second cradle and support to prevent a free movement therebetween, and a pair of radius

arms having one end pivotally connected to the top and bottom of said support in line with the central point of said vertically movable cradle and the other ends in fixed relation to said cradle, whereby said horizontally movable cradle will move in an arc with respect to said vertically movable cradle.

5 7. In a support for train pipe coupler heads, the combination of a drawbar having 10 slots extending transversely therethrough, a receptacle into which said drawbar may slide having a slot on each side thereof, members extending through the slots in said drawbar and said receptacle, and springs 15 cooperating with said members adapted to hold said drawbar in a predetermined position and permit its displacement axially in either direction from said normal position.

8. In a support for train pipe coupler 20 heads, the combination of a drawbar having a pair of oppositely disposed slots extending transversely therethrough, a receptacle into which said drawbar may slide having a single slot on each side thereof, members 25 extending through each pair of slots in said drawbar and engaging the slot in said receptacle, a spring within said drawbar between said members, and a spring between the innermost member and the end of said 30 receptacle adapted to cooperate with said first spring and said members to hold said drawbar in a predetermined position and permit its displacement axially in either direction from said predetermined position.
